UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK.

BRAKE SHOE FOR CAR RETARDERS.

Application filed October 10, 1927. Serial No. 225,301.

This invention relates in general to brake apparatus for location along a railway track for retarding cars as they pass thereby, generally known as car retarders or track brakes, and has more particular reference to the physical characteristics and particular conformation of a brake shoe employed in such brakes.

In retarders of the type in question, brake shoes are applied to opposite sides of the car wheels on passage of the car and exert their braking effect due to friction between the brake shoes and the car wheels. The brake shoes are worn away rather rapidly and require replacement at frequent intervals.

One object of the present invention is to provide a brake shoe which will wear longer than has heretofore been the case, and this is accomplished by using a brake shoe comprising a rolled steel section rather than employing a brake shoe of cast material, such as cast iron, or some special brake shoe metal.

It is a further object of this invention to decrease the cost of manufacture of the brake shoes while increasing the useful life of the same and also the efficiency thereof.

A further object is to decrease the amount of material used in making the brake shoes, facilitate the escape from the brake shoes of the heat generated by the frictional braking, and reduce to a minimum the amount of metal discarded when the brake shoe has to be replaced by a new one.

Further objects, purposes and characteristic features of this invention will appear as the description progresses, reference being had to the accompanying drawings showing, solely by way of illustration, one form of the invention. In the drawings:—

Fig. 1 is a transverse sectional elevation of a portion of a retarder including the present invention; and

Fig. 2 is a transverse sectional view, to an enlarged scale, of a brake shoe and brake beam in accordance with the present invention.

Referring to the drawings, and first more particularly to Fig. 1, there is shown one track rail 1 of a railway track, carried on ties 2, by means of clamping blocks 3, held to the ties by spikes 4.

Mounted on the clamping blocks 3 for sliding motion toward and away from the track rail 1, are brake beams 5 carrying brake shoes BS arranged to be forced into frictional engagement with either side of a car wheel 6.

Each brake beam has a spring guide 7, pivoted thereto by means of a pin 71, and carrying a spring 8 arranged to urge the brake shoe and brake beam inwardly toward the track rail 1. The present case does not show the slidable connection between the brake beams and the clamp blocks since this is fully set forth in applicant's co-pending application 70,599, filed Nov. 21, 1925, to which attention is here directed.

The brake shoe BS, as mentioned above, is formed of an integral piece of steel and rolled to the cross section shown in the drawing. It comprises a relatively narrow body 9, having an inwardly projecting head 10 at its upper end, and an inwardly projecting toe 11 at its lower end, the toe resting on, and being supported by an inwardly projecting shoulder 12 on brake beam 5.

For securely fastening the brake shoe to the brake beam screws 13 are employed, which pass through the brake beam as shown in Fig. 2 and through the body of the brake shoe just below the head 10, terminating flush with the inner face of the body 9. This provides a secure attaching means while permitting easy replacement of brake shoes when necessary.

The brake shoe, on its face toward the brake beam, is grooved out as shown at 14 and 15 in order to reduce the amount of metal in the shoe and at the same time provide an increased surface for radiation of the generated frictional heat.

With the brake shoe formed of rolled steel a much longer life is insured than is the case with such brake shoes as formally employed and made of cast material. Also, when the brake shoe must be discarded, due to wear, less metal need be thrown away than formerly, due to the configuration of the brake shoe and particularly to the grooved portions 14 and 15.

The screws 13, terminating flush with the inner face of the body 9 of the brake shoe, permit the braking head 10 to be worn down until its inner face is substantially flush with the inner face of the body. As shown in Fig. 1, the head 10 is positioned high enough up to bear with its entire friction surface against the car wheel 6, while the toe 11 is sufficiently low to clear the wheel and avoid any interference therewith.

It has been found in practice that under certain conditions the car wheels tend to ride up on the brake shoes, and in case they should

do so, the inwardly projecting toe 11, resting against the brake beam shoulder 12, will prevent any tendency to tip the brake shoe out of the vertical plane and avoid damage 5 to the braking apparatus.

The above rather specific description of this invention has been given solely by way of example, and is not intended, in any manner whatsoever, in a limiting sense. Obviously, the invention can assume various physical forms, and is susceptible of numerous modifications, and all such forms and modifications are intended to be covered by this invention, as come within the scope of the 15 appended claims.

Having described my invention, I now claim:—

1. In a car retarder, a brake beam and a brake shoe carried thereby, the brake shoe comprising a relatively narrow body, an inwardly projecting head at the upper end of the body for frictional engagement with a car wheel, an inwardly projecting toe at the lower end of the body, and a shelf on the 25 brake beam on which the toe rests.
2. In a car retarder, a brake beam and a brake shoe carried thereby, the brake shoe comprising a rolled steel section having a relatively narrow body, an inwardly projecting head at the upper end of the body for frictional engagement with a car wheel, an inwardly projecting support toe at the lower end of the body, and a shelf on the brake beam on which the toe rests. 30
3. In a car retarder, a brake beam and a 35

brake shoe carried thereby, the brake shoe comprising a relatively narrow body, an inwardly projecting head at the upper end of the body for frictional engagement with a car wheel, an inwardly projecting toe at the lower end of the body, a shelf on the brake beam on which the toe rests and means fastening the shoe to the beam and passing through the beam and the said body of the shoe and terminating flush with the inner 40 face of said body. 45

4. A car retarder brake shoe, comprising, a rolled steel section having a relatively narrow body, a friction head projecting inwardly from one end of the body, and a support toe 50 projecting inwardly from the other end of the body.

5. A car retarder brake shoe, comprising, a rolled steel section having a relatively narrow body, a friction head projecting inwardly from one end of the body, a support toe 55 projecting inwardly from the other end of the body, and grooved out portions in the outer face of said brake shoe.

6. A car retarder brake shoe, comprising, a rolled steel section having a relatively narrow body, a friction head projecting inwardly from one end of the body, a support toe 60 projecting inwardly from the other end of the body, and grooved out portions in the outer face of said shoe, the body being drilled parallel with said head for attachment of the brake shoe to operating means therefor. 65

In testimony whereof I affix my signature.
WINTHROP K. HOWE.
